ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

THREAD PARTING AND HOLDING MEANS FOR LOOMS.

1,134,487.

Specification of Letters Patent.

Patented Apr. 6, 1915.

Application filed July 7, 1914. Serial No. 849,605.

To all whom it may concern:

Be it known that I, ALONZO E. RHOADES, a citizen of the United States, residing at Hopedale, county of Worcester, State of 5 Massachusetts, have invented an Improvement in Thread Parting and Holding Means for Looms, of which the following description, in connection with the accompanying drawing, is a specification, like characters on 10 the drawing representing like parts.

This invention relates to means for parting the thread or filling in a loom and also to means for catching and holding the end of the parted thread or filling when for any 15 reason it is desirable so to hold such end.

The invention provides a novel means in a loom for parting the thread in that the thread is parted by abrasion, and particularly by the coöperating abrasive action of 20 two surfaces.

The invention also provides a novel means for catching and holding the parted end residing in the use of a member provided with a thread adhering surface, and more 25 particularly in a surface in which the thread adherent quality is secured by the fibrous condition of the surface, such for example as that presented by the edges of the superimposed washers of fibrous material such as 30 felt or cloth.

The invention more particularly relates to looms of the type wherein the running filling is replenished prior to complete exhaustion, the old or spent filling being parted 35 between the cloth and the shuttle, and the parted end caught and held to be carried into the path of a temple thread cutter or other suitable device for severing the filling close to the selvage. Features of the invention 40 in this particular connection reside in applying to the face of the running shuttle an abrading member or surface in providing a coöperative member having an abrading surface movable into the path of the 45 abrading surface upon the running shuttle so that when the movable member at the required time is brought into the path of the shuttle the running filling is severed by the coöperative abrading action of the two 50 surfaces, and further in providing a means located adjacent to and preferably movable with the aforesaid coöperating member to 55 catch and hold the parted filling end by adherent action such as the action of a fibrous surface.

The invention also involves novel features of construction and operation in such a mechanism, and is herein shown in a preferred embodiment in connection with a loom such as that of the well known "Northrop" type.

The nature of the invention will appear more fully from the accompanying description and drawings and will be particularly pointed out in the claims.

The drawings illustrate a preferred form of thread parting means, and means for catching and holding the parted end embodying the invention, together with so much of the loom construction as is necessary to an understanding of the invention.

In the drawings, Figure 1 is a vertical cross sectional view of a portion of a loom of the "Northrop" type looking toward the hopper mechanism and showing in side elevation the parts particularly concerned with this invention the part 31 being shown in dotted lines for the sake of clearness; Fig. 2 is an elevation of the parts particularly concerned with this invention looking from a point in front of the lay toward the front of the loom; Fig. 3 is a top plan view of the main parts shown in Fig. 1; Fig. 4 is a side elevation of one end of a shuttle with the abrading member of this invention in position.

While the broad features of the invention are applicable to various means for parting thread in a loom for any desired purpose, the invention in its more specific form is concerned with the parting of the running filling prior to transfer in an automatic filling replenishing loom such as that of the "Northrop" type. Mechanisms for securing this general object by other means are well known and familiar, and are commonly associated with or operated by the well known shuttle feeler mechanism or the mechanism which detects the presence of an improperly boxed shuttle and automatically prevents the transfer of filling taking place. The preferred construction of the present invention herein illustrated is for convenience shown in connection with a well known type of shuttle feeler mechanism, and is shown as having its operation effected by such shuttle feeler mechanism.

The construction of loom and shuttle feeler mechanism herein disclosed as a basis for the disclosure of the present invention is

similar to that shown in the patent to Davis No. 1,084,878 granted January 20, 1914, and the patents therein referred to, but has one essential difference in that the shuttle feeler 5 herein illustrated has no sliding movement axially of its pivotal axis because such movement is unnecessary when the present invention is used in the form illustrated.

The lay 1, the breast beam 2, the hopper 10 stand 3, the notched dog 4 pivoted to the depending arm 5 of the transferrer, the controlling rock shaft 6 actuated upon the call for filling replenishment, and the vertical supporting member 7 of the loom side are all 15 well known and familiar to this type of automatic filling replenishing loom, and with their adjunctive features are more fully illustrated and described in the patents above referred to.

20 The shuttle feeler mechanism as already noted is of the general type shown in the patent to Davis above referred to, the construction being altered to provide for the elements embodying a preferred form of the 25 present invention. A bracket 8 is bolted at 9 to the loom side and projects rearwardly therefrom. The shuttle feeler 10 is provided with a hub 11 offset from the shank or body of the feeler and pivoted or fulcrumed on a 30 stud 12 projecting from the bracket 8. This shuttle feeler is provided on its shank with a hub 13 to which is bolted the cam slotted arm 14 which engages and operates the dog 4 to swing it into the path of a bunter upon 35 the lay and operates the transferrer mechanism in a well known manner. A pin 15 projects laterally from the shank of the shuttle feeler above its fulcrum and is operatively connected with the controlling rock 40 shaft 6 by the arm 16 and jaw 17 governed by the spring 18. The jaw 17 is fulcrumed at the knife edge 19 on the arm 16. It will thus be seen that with this familiar construction upon the call for filling replenishment the arm 16 will be swung upwardly 45 allowing the shuttle feeler 10 to swing rearwardly under the influence of the spring 18 and effect its functions in the usual manner. The shuttle feeler and actuating connections 50 are shown in this position in the drawings. The rearward movement of the shuttle feeler is limited by a projection 101 from the shank thereof, engaging beneath a projection 102 from the bracket 8, while the forward movement of the parts is limited by another projection 103 on the bracket 8.

55 The features already described are all well known to those familiar with this type of loom except that it will be noted that the 60 shuttle feeler 10 has no transverse movement but swings in a single plane, the transverse movement being unnecessary when the present invention in its preferred form is employed. The remaining features illustrated in the drawings embody a preferred

form of the invention. A movable supporting member shown as an oscillating arm 20 is provided with a laterally projecting hub 21 journaled on the stud 12, and is held in place thereon by a washer 22 and a cotter pin 23. An arm 24 projects forwardly from and rigidly with the hub 21 and carries a pin 25 which alines with the pin 15 and likewise extends between the arm 16 and the jaw 17. The movable supporting member 20 75 serves to support and impart movement to one of the abrading surfaces, thus to bring them into coöperative relation and enable the thread to be severed. For this purpose in the form shown the movable supporting 80 member 20 has at its upper end an elongated grooved head 26 in which is slidably mounted the shank 27 of the carrier 28. The carrier 28 is provided with a face which is struck by the lay as the lay beats up. The carrier 85 is provided with the abrading member 29 which may be a piece of hardened steel presenting preferably a cylindrical abrading surface. This abrading member is preferably a separate piece secured in place by 90 screws 30. It will thus be seen that the two abrading members have a relative lateral movement to effect the abrading action caused in the form illustrated by the passage of the shuttle abrading surface 43 laterally 95 past the abrading surface 29, and that they also have a relative transverse movement to bring them into coöperative relation caused in this case by the arm 20 being thrown rearwardly automatically at the required time to 100 carry the abrading surface toward the shuttle and the shuttle carrying its abrading surface 43 forwardly upon the beat up of the lay. The head of the carrier 28 is also elongated and carries at a position toward 105 the center of the loom the thread catching and holding member 31 which as shown comprises a series of superimposed disks of felt, cloth or similar material, the cylindrical surface of which member thus presents a 110 thread adherent surface, that is, a surface upon which the thread or filling will catch and be held by adhesion. This member need not necessarily be mounted upon the same carrier as the adjacent abrading member, as 115 it is not essential that these two members shall be operated simultaneously and with the same extent of movement, but simplicity of construction and operation is effected by the arrangement illustrated and described. 120 The shank 27 of the carrier is provided with a stud or pin 32 which projects through and rides in a slot shown in dotted lines in Fig. 1 in the forward portion of the movable supporting member 20. A rearward movement 125 toward the lay of the carrier with respect to the movable member is effected by an actuating lever 33, the upper end of which is slotted to engage a pin 34 projecting from the shank 27 of the carrier. This lever 33 130

is provided with a hub 35 journaled on a pin 36 projecting from the shank of the supporting member 20 above its fulcrum. A helical spring 37 surrounds the hub 35 and 5 engages at one end the lever 33 and at the opposite end a nut 38 on the stud 36. The lever 33 extends below its fulcrum point and the depending portion 39 contacts with a lateral projection 40 from the bracket 8.

10 The shuttle 41 is provided on its face adjacent the thread eye 42 with a coöperating abrading member which is herein shown as a small piece of hardened steel 43 secured by the screw 44 and presenting a cylindrical 15 abrading surface.

The operation of the mechanism will now be apparent. Upon call for filling replenishment the controller rock shaft 6 is operated to raise the arm 16. Spring 18 pulling 20 upon the jaw 17 simultaneously swings the shuttle feeler 10 and the movable supporting member 20 rearward into the position shown in the drawings, this movement being limited by the stop projection 102. At the 25 same time, the dog 4 is thrown by the connection 14 from the shuttle feeler into the path of the usual bunter. As the movable support 20 swings rearwardly it carries with it the fulcrum or pivot 36 and as the 30 lower end of the lever 33 engages the fixed portion of the bracket the upper end of the lever 33 moves rearwardly under the influence of the spring 37, thus sliding rearwardly the carrier 28 with respect to the 35 slotted head of the movable member 20 bringing these parts also into the position shown in the drawings. In this position the face of the carrier 28 is in position to be struck by the lay as it beats up, and thus 40 the carrier is slid back in the head of the movable member 20 against the action of the spring 37. The abrading member 29 and the thread adherent member 31 which are mounted to project over the lay are thus 45 presented and maintained in operative position for securing their functions. As the shuttle is picked into the box at the transfer end of the loom the abrading surface 43 carried thereby and over which the running 50 filling extends from the thread eye 42 locks against the abrading surface 29 held yielding rearward, and the thread is parted by the coöperating action of these two abrading surfaces. The parted end of the 55 thread or filling extending from the fell is in contact with the thread adherent surface of the member 31 and is caught and held thereon by the adhesive action of the surface. The parts now return to their inoperative 60 position and the parted end of the thread or filling adhering to the member 31 is carried forward and the filling passes into the field of action of the usual temple thread cutter in the usual manner, not necessary here to illustrate. While the member

31 moves forwardly in a rectangular direction the distance from it to the point at which the filling end is held in the fell increases, but no lateral movement of the member 31 is necessary because the filling 70 end being held by adherent action thereon may slip or give with respect thereto without being pulled away therefrom.

Having fully described my invention, what I claim as new and desire to secure by 75 Letters Patent is:

1. In an automatic filling replenishing loom, means for parting the running filling comprising an abrading surface located on the shuttle in the path of the filling, a member provided with a coöperating abrading surface, and means for moving said member to carry the coöperating abrading surface into the path of the abrading surface on the shuttle to effect the parting of the filling 80 by the coöperative action of said abrading surfaces.

2. In an automatic filling replenishing loom, means for parting the running filling comprising an abrading surface located on 90 the shuttle in the path of the filling, a member provided with a coöperating abrading surface, and means for moving said member to carry the coöperating abrading surface into the path of the abrading surface on 95 the shuttle to effect the parting of the filling by the coöperative action of said abrading surfaces, and means located adjacent to and movable with said member to catch and hold the parted filling end. 100

3. In an automatic filling replenishing loom, means for parting the running filling comprising an abrading surface located on the shuttle in the path of the filling, a member provided with a coöperating abrading surface, and means for moving said member to carry the coöperating abrading surface into the path of the abrading surface on the shuttle to effect the parting of the filling by the coöperative action of said 110 abrading surfaces, and means located adjacent to and movable with said member to catch and hold by adherent action the parted filling end.

4. In an automatic filling replenishing 115 loom, means for parting the running filling comprising an abrading surface located on the shuttle in the path of the filling, a member provided with a coöperating abrading surface, and means for moving said member 120 to carry the coöperating abrading surface into the path of the abrading surface on the shuttle to effect the parting of the filling by the coöperative action of said abrading surfaces, and means located adjacent to and 125 movable with said member presenting a thread adherent surface to catch and hold the parted filling end.

5. In an automatic filling replenishing 130 loom, means for parting the running filling

- comprising an abrading surface located on the shuttle in the path of the filling, a member provided with a coöperating abrading surface, means for moving said member to 5 carry the coöperating abrading surface into the path of the abrading surface on the shuttle to effect the parting of the filling by the coöperative action of said abrading surfaces, and means located adjacent to and 10 movable with said member presenting a fibrous thread adherent surface to catch and hold the parted filling end.
6. In a loom, thread parting means comprising a pair of coöperating abrading members relatively movable both laterally and 15 transversely of each other, means for automatically effecting said relative transverse movement of said members to bring them into coöperative relation when it is desired 20 to part the thread, and means for thereafter effecting said relative lateral movement of said members whereby the thread will be parted upon the occurrence of said relative lateral movement.
- 25 7. In a loom, the combination of thread parting means, a member comprising a series of superimposed washers of fibrous material, the edges of which present a thread adherent surface to catch and hold the parted thread end, and means for giving a bodily movement to said member to bring it into 30 position to catch and hold the parted end.
8. In an automatic filling replenishing loom, a shuttle provided with a thread 35 abrading surface in the path of the running filling, a supporting member movable toward and from the lay, a carrier mounted on said member and movable independently toward and from the lay, an abrading surface 40 on said carrier adapted to coöperate with that on the shuttle, and means for moving said carrier yieldingly toward, and positively from, the lay with respect to said member.
- 45 9. In an automatic filling replenishing loom a shuttle provided with a thread abrading surface in the path of the running filling, a supporting member movable toward and from the lay, a carrier mounted 50 on said member and movable independently toward and from the lay, an abrading surface on said carrier adapted to coöperate with that on the shuttle, means for moving

said carrier yieldingly toward, and positively from, the lay with respect to said member, and a positioning surface on said carrier in the path of the lay and adapted to be struck by the lay on the beat up to position and maintain the abrading surface on the carrier in the path of the abrading surface on the shuttle.

10. In an automatic filling replenishing loom, a shuttle provided with a thread abrading surface in the path of the running filling, a movable carrier provided with a coöperating abrading surface, and means for moving said carrier yieldingly toward and positively from the lay whereby the carrier when moved toward the lay will position the abrading surface carried thereby in the path of that on the running shuttle to cause the parting of the filling.

11. In an automatic filling replenishing loom, a shuttle provided with a thread abrading surface in the path of the running filling, a carrier provided with a coöperating abrading surface, and means actuated upon the call for filling replenishment to move and hold said carrier yieldingly toward the lay, whereby upon the beat up of the lay and as the shuttle reaches the transfer end of the loom the said abrading surfaces act to part the filling.

12. In an automatic filling replenishing loom, means for parting the running filling comprising an abrading surface located on the shuttle in the path of the filling, a member provided with a coöperating abrading surface, and means for moving said member to carry the coöperating abrading surface into the path of the abrading surface on the shuttle to effect the parting of the filling by the coöperative action of said abrading surfaces, and a positioning surface on said member in the path of the lay and adapted to be struck by the lay on the beat up to position and maintain the abrading surface on said member in the path of the abrading surface on the shuttle.

In testimony whereof, I have signed my name to this specification, in the presence of two subscribing witnesses.

ALONZO E. RHOADES.
